BY

Harry H. Styll.
ATTORNEY

UNITED STATES PATENT OFFICE.

WILLIAM H. BOUTELLE, OF STURBRIDGE, MASSACHUSETTS, ASSIGNOR TO AMERICAN OPTICAL COMPANY, OF SOUTHERBRIDGE, MASSACHUSETTS, A VOLUNTARY ASSOCIATION OF MASSACHUSETTS.

EYEGLASS GUARD.

Application filed May 23, 1923. Serial No. 640,844.

To all whom it may concern:

Be it known that I, WILLIAM H. BOUTELLE, a citizen of the United States, residing at Sturbridge, in the county of Worcester and 5 State of Massachusetts, have invented certain new and useful Improvements in Eyeglass Guards, of which the following is a specification.

This invention relates to improvements in 10 eyeglass guards and a method of producing same, and has particular reference to guard pads having a composition covering for their faces.

Prior to my invention guard pads have 15 been made with a metal backing, to the face of which is secured, by rivets, a piece of composition material. The metal pins or rivets appearing in the face of the pad are attacked chemically by perspiration when warm, this 20 chemical action rendering the pad unsanitary and disagreeable in appearance.

One object of the present invention is to produce an eyeglass guard pad having a composition face without any metallic attaching parts.

Another object is to provide a guard pad of improved construction whereby the use of small pins or rivets is dispensed with, and the cost of manufacture will be lessened.

30 A further object is to provide an improved method of assembling such pads.

Other objects and advantages will be apparent from the following description taken in connection with the accompanying drawings, wherein are shown preferred embodiments of the invention.

In the drawings:

Figure 1 is a front elevation of an eyeglass embodying the invention.

40 Figure 2 is an elevation of the guard.

Figure 3 is a rear elevation of the guard pad illustrating the method of connecting it to the guard.

Figure 4 is a vertical transverse sectional view on the line 4—4 of Figure 3.

45 Figure 5 is a detail perspective view of one of the elements of the improved pad.

Figure 6 is a similar view of the metallic core.

50 Figure 7 is a similar view of the outer composition cover.

Figures 8 and 9 are views similar to Figure 4 illustrating modifications.

Similar reference characters designate

corresponding parts throughout the several 55 views.

I have illustrated my improved pad as applied to a fingerpiece mounting, which comprises the usual bridge 10 carrying at each end thereof a lens 11, and adjacent each 60 end the usual pivot post 12. Mounted upon the pivot post 12 is the usual fingerpiece 13 carrying at its inner extremity the guard 14, said guard being provided at its upper side with an offset arm 15 having at its 65 extremity a head 16.

The numeral 17 designates the pad, generally said pad being composed of a metal plate 18 having on one surface a stud 19 which is receivable in an aperture in the 70 head 16 of the guard, and riveted over as indicated at 20. The union between the guard and the pad is quite loose, such that the pad will be able to move in relation to the guard so as to readily conform to the 75 shape of the wearer's nose. A composition disc 21 having a central aperture 22 is mounted upon the plate 18 with the stud 19 extending through the aperture. The peripheral edges of the plate 21 may be offset 80 as clearly shown in Figure 4, and a second composition plate 23 may be applied to the outer face of the plate 18. The plates 23 and 21 are then cemented together as at 24, whereby the metal plate 18 is completely 85 covered by a composition material and no metal appears on the face of the finished pad. The outer surface of the plate 23 may be suitably corrugated or roughened as at 25 if desired. 90

In Figure 8 I have shown a modification wherein the inner composition cover 27 is provided with a recess 26, wherein the plate 18 is receivable and the stud 19 projecting beyond the plate 27 as illustrated. 95

Figure 9 is a representation of another modification wherein the metal plate 18 is set into an aperture in a sheet of composition material 28, said composition material being of the same thickness as the plate 18. 100 Then the inner and outer coverings of zylonite 21 and 23, respectively, are applied and cemented to the sheet 28, as shown at 24.

From the foregoing description it will be readily apparent that I have produced an 105 improved guard for eyeglasses wherein no metallic parts will touch the face and, therefore, the pad will be very sanitary and du-

rable. I have provided a novel method of assembling such articles whereby the cost of assembly is greatly reduced and the use of expensive dies and small rivets is eliminated. Obviously changes may be resorted to in the form and arrangement of parts, and I reserve the right to make such changes falling within the scope of the appended claims without departing from the spirit of 10 my invention.

Having thus described my invention, what I claim is:

1. In a guard for an ophthalmic mounting, a metallic face plate with an offset stud, 15 a non-metallic facing on the front of the metallic face plate extending beyond the edges thereof, a non-metallic facing on the back of the metallic face plate having a portion covering the back face of the face plate 20 around the offset stud, and a portion extend-

ing beyond the edges of the face plate and engaging the front non-metallic facing beyond the edges of the metallic face plate, and cementitious means for uniting the front and back non-metallic facings.

2. In a guard for an ophthalmic mounting, a metallic face plate with an offset stud, a composition facing on the front of the metallic face plate extending beyond the edges thereof, a composition facing on the 30 back of the metallic face plate having a portion covering the back face of the metallic face plate around the offset stud, a portion extending beyond the edges of the metallic face plate, and engaging the front composition facing beyond the edges of the metallic face plate, and cementitious means for uniting the composition members together.

WILLIAM H. BOUTELLE.
